UNITED STATES PATENT OFFICE.

MAX RALL, OF STUTTGART, GERMANY, ASSIGNOR TO ROBERT BOSCH AKTIENGESELLSCHAFT, OF STUTTGART, GERMANY.

PLANT FOR THE SUPERVISION OF THE CIRCULATION LUBRICATION ON POWER CARS.

Application filed May 26, 1922. Serial No. 563,992.

To all whom it may concern:

Be it known that I, MAX RALL, a citizen of Germany, residing at Stuttgart, Germany, have invented certain new and useful Improvements in a Plant for the Supervision of the Circulation Lubrication on Power Cars, of which the following is a specification.

For the supervision of the circulation of the lubrication oil on power vehicles, mechanical indicators have already been devised which are inserted into the pressure or delivery pipe for the lubricating oil and indicate by the position of a movable member whether or not the pressure in that pipe is that required. The indicating member is, however, but difficultly to be discerned from some distance, and superintending the lubrication at night by that means is extremely unreliable.

These draw backs are obviated by means of the present invention, the gist of which consists in making a member, acted on by the oil-pressure, control a contact inserted into the circuit of an electric indicating means, such as a lamp or the like, in such a manner, that the lamp etc. is switched in only when, or after, a certain oil pressure is, or has been reached. If the respective power vehicle is equipped with a lighting dynamo, the circuit of the lamp or other indicating means is preferably connected up directly to the terminals of that dynamo, but not branched off behind the usual automatic switch between the dynamo and the battery, the purpose of the first-mentioned arrangement being to prevent the supervision means for the circulating lubrication oil from being injuriously acted on in the case of the switch becoming defective. Besides, a special switch for the control-circuit may be dispensed with.

My invention is illustrated by way of example in the accompanying drawing, in which Fig. 1 is a diagrammatical representation of a plant embodying that invention. Fig. 2 is a modified detail, viz., of the members 4 and 5 of Fig. 1.

Connected with the pressure or delivery pipe 1 of the oil circulation pump 2 is a box 3 which is closed at its top by a diaphragm 4, that bulges out more or less according to the pressure of the oil in the pipe 1. The diaphragm acts upon a contact 5 inserted into a circuit 6 connected up directly to the

terminals of the lighting dynamo 7 and having inserted into it the indicating lamp 8. This circuit is perfectly independent of the automatic switch 9 and the other lamp circuit 10 so that the lubrication may be constantly and automatically superintended.

In Fig. 1 the contact 5 is broken, as is consequently also the circuit 6 of the lamp 8, thus indicating that the pressure of the oil in the pipe 1 has the proper height. This being so, the diaphragm is so much bulged out that, as shown, the contact 5 is broken. But as soon as the pressure of the oil in the pipe 1 sinks to or below a certain predetermined degree, the diaphragm 4 is bulged out correspondingly less or, may be, not at all, so that the contact 5 is closed. At once the lamp 8 lights up, indicating a disturbance in the lubrication conduit.

Connecting up the circuit 6 directly to the terminals of the lighting dynamo offers the advantage that the plant is independent of the position of the automatic switch 9 so that the driver is not compelled to change now and then the position of this switch in order to ascertain the condition of the plant. This examination proceeds quite automatically when the motor is started and stopped.

When starting the motor, the lamp 8 does not immediately light up because a current of sufficient strength is not instantly generated, but after a very short time sufficient current is generated and the lamp lights up, on the one hand because there is sufficient current in the circuit 6, and on the other hand, because there is not yet sufficient pressure in the oil pipe 1. But again after a short time the engine has produced the requisite pressure in the pipe 1, the diaphragm 4 bulges out, the contact 5 is broken, and the lamp 8 is extinguished.

The same occurs when the motor is stopped. The pressure in the pipe 1 falls at once, as does also the diaphragm and the circuit is closed at 5. The lamp then lights up, but only for quite a short time, because the current which the dynamo is still generating is soon too much diminished to maintain the lamp burning. It is merely a short lighting up by which the driver sees that the plant is in proper working condition.

While, in the form of construction of the contact shown in Fig. 1 at 5 the circuit is opened when the proper pressure has been

reached in the pipe 1, it is closed in the modified form of construction shown in Fig. 2. This is at once obvious without a detailed explanation. The lamp is thus 5 burning as long as that pressure is maintained.

It is also obvious that the lamp 8 may be replaced by any other suitable indicating means, for instance a rotary disk, a hand 10 and the like. Making use of a lamp offers the advantage that the lubricating installation may be superintended also in the evening and at night-time and with the same reliability as at day-light.

15 The circumstance that the indicating installation operates only when the lighting dynamo operates is of no consequence because also the circulation-lubrication operates only when the car motor is running.

20 Having now described my invention, what I claim as new and desire to secure by Letters Patent of the United States is:

1. In a device of the class described, the combination, with an engine, an oil circulating system for said engine, and means driven by the engine for forcing oil under pressure through said system, of a member 25 adapted to be controlled by the pressure of the oil in said system, electric indicating

means, a dynamo operated by said engine, 30 an electric circuit connected directly to the terminals of said dynamo, said indicating means being connected in said circuit, and a circuit breaker connected in said circuit and controlled by such oil-pressure-con- 35 trolled member.

2. In a device of the class described, the combination, with an engine, an oil circulating system for said engine, and means driven by the engine for forcing oil under 40 pressure through said system, of an electric lamp, a dynamo operated by said engine, an electric circuit connected directly to the terminals of said dynamo, said lamp being connected in said circuit, and means in said 45 oil circulating system including a dia- phragm for maintaining the electric circuit open when the oil in said system exceeds a certain pressure and to allow the circuit to close when the oil falls below a certain pres- 50 sure.

In testimony whereof I have affixed my signature in presence of two witnesses.
